UNITED STATES PATENT OFFICE.

HENRY KLECKLER, OF GARDEN CITY, NEW YORK, ASSIGNOR TO CURTISS AEROPLANE AND MOTOR CORPORATION, A CORPORATION OF NEW YORK.

FLYING-BOAT.

1,336,634.

Specification of Letters Patent. Patented Apr. 13, 1920.

Application filed March 25, 1918. Serial No. 224,541.

To all whom it may concern:

Be it known that I, HENRY KLECKLER, a citizen of the United States, residing at Garden City, in the county of Nassau and State 5 of New York, have invented certain new and useful Improvements in Flying-Boats, of which the following is a specification.

My invention relates to hydro-aero-machines and is an improvement upon the 10 invention of myself and Glenn H. Curtiss described and claimed in application Serial No. 138,633, filed December 3, 1916. Unlike the former the present invention is characterized by a single spar or outrigger rear- 15 wardly extending from the hull at or near its amidships section, to the empennage. This spar reinforces and strengthens the tail structure of the hull, which is comparatively light, takes up the inertia of the empennage 20 in landing, and carries the major portion of the lift load of the tail unit or empennage under certain conditions of flight. The invention is further characterized by an improved and somewhat different type of engine 25 mounting. Instead of the conventional V-support a substantial M-support is provided. The upwardly converging legs of the M-support are fastened to the respective engine bed beams by suitable fittings com- 30 mon to the adjacent struts. This M-brace or support together with a forwardly and downwardly inclined post brace take up not only the inertia stress in landing but the thrust effort of the power plant while the 35 machine is in flight. The power plant is of the single unit type and consists of a high-powered motor, a fuel supply system (including lubricant tanks) a radiator and propeller. The radiator is mounted at the for- 40 ward end of the engine bed and the propeller (of the pusher type) at the opposite end thereof. The general arrangement of the various elements of the power plant and the relative location of these elements with 45 respect to the supporting surfaces and engine bed constitute further features of novelty which will be hereinafter more fully explained.

Of the drawings, wherein like characters 50 of reference designate like or corresponding parts:—

Figure 1 is a side elevation of the ma-
chine;

Fig. 2 is a top plan view;

Fig. 3 is a front end elevation of the mo- 55 tor support or engine mounting; and

Fig. 4 is a side elevation of that portion of the machine illustrated in Fig. 3.

The hull or body of the craft designated as an entirety by the numeral 10 is shown as 60 of the conventional Curtiss type having lateral fin excrescences 11, a rearwardly facing step 12, a relatively broad and comparatively flat hydroplaning bottom 13, empennage 14, supporting surfaces 15 and 16, motor 17, 65 propeller 18 and ailerons 19. That portion of the hull 10 to the rear of the step 12 constitutes the after body as distinguished from the fore body. This after body or tail is lighter per unit of length than the fore body 70 and is consequently weaker. As the landing and hydroplaning stresses are borne almost entirely by the fore body of the hull such a construction is permissible. It is essential however that adequate strength be provided 75 at the tail end of the hull to carry the stresses set up in the empennage. The empennage comprises the usual vertical rudder 20, elevator flaps 21, vertical stabilizer 22 and horizontal stabilizer 23. In view of 80 the elevated position of the motor 17 the horizontal stabilizer 23 and elevator flaps 21, which are in direct rearward continuation of said stabilizer, are spaced vertically some distance above the tail end of the hull. Be- 85 ing thus spaced it is necessary that some means be provided for carrying the lift and other stresses into the hull, preferably at or near its amidships section. The sta- 90 bilizer 23 being of the lifting type the lift load imposed upon it under certain conditions in flight is oft times large and it is to carry this load into the hull that the spar or outrigger 24 is provided. It extends di- 95agonally forwardly and downwardly from the leading edge of the stabilizer in the longitudinal vertical plane of the fore and aft axis of the hull for connection at its for- 100 ward end to the rear wing beam 25 of the lower supporting surface 16 at a point within the hull or body. Suitable interior hull bracing such as I have indicated by dotted lines in Fig. 1 of the drawings effectually distributes the stresses imposed upon the spar 24 over a wider area of the hull bottom. The 105 spar, during flight of the aeroplane, not only braces the tail unit but, as before intimated, takes up the entire inertia stress set up by

the empennage in landing. It also stiffens the tail of the hull throughout its full length and with the vertical fin 22 constitutes a substantially right triangular truss, the tail 5 of the hull being the base of the triangle, the vertical fin 22, the altitude, and the diagonal spar 24 the hypotenuse. Moreover, the location of the stabilizer 23 and elevators 21 in the direct slip stream of the propeller is desirable in that the effectiveness of 10 not only the elevator flaps but the vertical rudder as well is increased and the desired lift of the fin 23 assured.

Between the supporting surfaces 15 and 15 16 and in the longitudinal vertical plane of the fore and aft axis of the craft the motor 17 is located. It is supported in place by engine bed beams 26 arranged in parallelism. The engine bed beams are in turn supported by substantially M-braces or supports 20 27 founded upon the respective wing beams of the lower wing. The forward M-brace is inclined slightly rearwardly from the vertical plane to engage the beams 26 at points 25 directly beneath the forward end of the motor crank case. The M-brace 27 is more nearly vertical and likewise engages the beams 26 at points near the rear end of the motor crank case. The center legs of the 30 M-braces and the outer legs of the M-braces are brazed or welded together at their upper ends to fittings 28 of substantially U-form which embrace the respective wing beams at the points mentioned. In other words, one 35 socket is provided for two legs of each brace. In addition to the forward M-brace 27 which takes up some slight portion of the inertia stress of the motor mass and the thrust effort of the propeller there is provided a 40 forward diagonal post brace 29. At its forward lower end it is carried into the fore body of the hull and anchored by any suitable means to the hull bottom. At its rear upper end it is equipped with a Y-fitting 45 30, the diverging legs of which extend to the respective engine bed beams where they are fastened as at 31 at points slightly removed from the points of attachment of the forward M-brace 27. A suitable socket 50 32 is provided for attaching the post brace 29 to the Y. The function of the post brace is to carry the thrust effort of the propeller and the inertia stress of the motor mass into the fore body of the hull where it is distributed 55 over the hydroplaning area of the hull bottom.

Inverted V-braces or struts 33 interconnect the engined bed beams with the upper supporting surface 15. They are suitably 60 spaced fore and aft to accommodate the motor 17, and in the embodiment disclosed are slightly out of vertical alinement with the M-braces 27. Both of them are slightly forwardly inclined from the engine bed for 65 attachment with the wing beams 34 of the

upper wing. By thus inclining them to be vertical they are caused to take up a small portion of the thrust effort of the propeller and the inertia stress of the motor mass. They are spaced however out of alinement 70 with the M-braces in order that the motor may be accommodated between them.

At the extreme forward end of the engine bed a radiator bracket 35 is provided. Its construction is such that the beams 26 75 are cross-braced and the radiator supported above them rather than at a forward point. Lugs 36 formed upon the bracket overlap the respective engine bed beams and with that portion of the bracket arranged between the beams they constitute a rigid beam connection and brace. The radiator designated as 37 is supported upon the bracket and its size is such that the cap 38 is let through the nose end of the upper supporting surface as illustrated in Figs. 3 and 4. It is thus conveniently situated and partly inclosed within the confines of the upper wing.

A streamline gravity fuel feed tank 39 is 90 mounted upon the upper supporting surface 15 directly above the motor. It is of substantially streamline form except for its sump 40. The sump however is let into the upper supporting surface where it is removed from the line of air rush to minimize head resistance in flight. The depth of the sump is such that its connection 41 with the feed line (not shown) to the motor extends beneath the under surface of the ring.

In addition to the gravity fuel feed tank 39 smaller tanks 42 are provided. These tanks contain lubricant and are disposed symmetrically at opposite sides of the engine bed for attachment with its respective beams by straps 43 and brackets 44. The straps embrace the tanks 42 and the brackets contact the beams. The tanks 42 are also of substantially streamline form.

The provision of M-braces beneath the engine bed is desirable in view of the fact that the weight of the motor mass is distributed over a wider area of the hull and at points best designed to carry it. The diverging legs of the M-braces engage the 115 respective wing beams of the lower wing at points in substantially the vertical plane of the hull sides and the converging legs at points substantially in the vertical plane of the fore and aft axis of the hull, i. e., its 120 keel line which is strongest. Their connection with the wing beams is such that the vibrational strains of the motor will not tend to loosen or weaken them. In other words the M-braces support the single centrally located engine bed so that it is of twice the strength and may support twice the weight of the engine beds supported solely by the conventional V-braces used heretofore.

While I have described my invention in detail in its present preferred embodiment, it will be obvious to those skilled in the art after understanding my invention, that 5 various changes and modifications may be made therein without departing from the spirit or scope thereof, and I aim in the appended claims to cover all such modifications and changes.

10 What is claimed is:

1. An airplane comprising a body, an aerial supporting surface arranged transversely thereof, an empennage, and a brace for the empennage extended at its forward 15 end into the body at or near the point of intersection of the supporting surface.

2. An airplane comprising a body, an aerial supporting surface arranged transversely thereof, a beam incorporated in the 20 supporting surface and extended into the body, an empennage, and a brace for the empennage extended at its forward end into the body for connection with the beam.

3. An airplane comprising a body, super- 25 posed aerial supporting surfaces arranged transversely thereof, a beam incorporated in the lower supporting surface and extended through the body, an empennage, and a brace for the empennage extended at its forward end into the body for connection 30 with the beam.

4. In an airplane, the combination, of a body, an aerial supporting surface arranged transversely thereof, a power plant including a pusher propeller having an axis of 35 rotation in vertical alinement with the fore and aft axis of the body, an empennage mounted at the rear end of the body, and a brace of the empennage forwardly and downwardly inclined for connection with 40 the supporting surface, the brace at its extreme forward end lying directly beneath the propeller.

5. In an airplane, the combination, of a body, superposed aerial supporting surfaces 45 arranged transversely thereof, a beam incorporated in the lower supporting surface and extended through the body, an empennage including a horizontal stabilizer, the empennage being mounted at the rear end 50 of the body, a power plant including a pusher propeller having an axis of rotation in vertical alinement with the fore and aft axis of the body and a brace for the empennage forwardly and downwardly inclined for connecting with the beam, the brace at its forward end being extended into 55 the body at a point directly beneath the propeller.

In testimony whereof I hereunto affix my 60 signature.

HENRY KLECKLER.
